The ornamental design for blender attachment, as shown and described.

DESCRIPTION

FIG. 1 is a perspective view of a blender attachment, showing our new design in another embodiment; FIG. 2 is a front view of the embodiment shown in FIG. 1; FIG. 3 is a back view of the embodiment shown in FIG. 1; FIG. 4 is side view of the embodiment shown in FIG. 1; FIG. 5 is another side view of the embodiment shown in FIG. 1;

FIG. 6 is a top view of the embodiment shown in FIG. 1; FIG. 7 is a bottom view of the embodiment shown in FIG. 1; and

FIG. 8 is a cross-sectional view of the embodiment shown in FIG. 4, taken along lines 8-8; and, FIG. 9 is another perspective view of the embodiment shown in FIG. 1, as shown in a blender environment.

The broken lines in the figures are for environmental purposes only and form no part of the claimed design.

The stippling represents a contrast in appearance and/or material from the other claimed portions of the design.
